UNITED STATES PATENT OFFICE.

JOHN GEORGE SMITH, OF MUSWELL HILL, LONDON, ENGLAND.

LAMP, SEARCHLIGHT, AND THE LIKE.

Application filed March 9, 1923. Serial No. 623,986.

To all whom it may concern:

Be it known that I, JOHN GEORGE SMITH, a subject of the King of Great Britain, and resident of Muswell Hill, London, England, 5 have invented certain new and useful Improvements in or Relating to Lamps, Searchlights, and the like, of which the following is a specification.

This invention relates to lamps, searchlights and the like, and more particularly to head-lamps such as are used on motor vehicles, and has for its object to provide a lamp that will give the desired illumination at a given range without objectionable glare, 15 or with the glare reduced to a minimum.

The present invention comprises a beam projecting lamp having an ordinary parabolic reflector, and a source of light arranged at or near the focus thereof, and also an 20 obturator co-axially arranged in the projected beam, wherein the rays from the parabolic reflector are reflected from a co-axial conical reflector on to an annular reflector arranged to reflect them to produce the de- 25 sired projected beam, the co-axial conical reflector acting as the obturator. The de- sired projected beam may be, for instance, one giving at a range or distance of 200 30 feet a disc of illumination of 20 feet di- ameter.

Various embodiments of the invention are illustrated diagrammatically by the accompanying drawings, wherein:

Figure 1, is a longitudinal section of a 35 lamp showing a double distribution of the projected rays at a given range or distance.

Figure 2, is a diagrammatic section of a 40 similar lamp showing a single distribution of the projected rays at a given range or distance.

Figure 3, is a similar section of a lamp having a series of concentric annular reflectors.

Figure 4, is a section of a modification 45 of the lamp having the inner conical reflector and the parabolic reflector reversed.

Figure 5, is a modification of the lamp shown in Figure 4, with the conical reflectors of parabolic contour.

50 The reflectors shown in the drawings are all co-axial with the projected beam, and the parallel rays referred to herein are rays from the ordinary parabolic reflector.

In Figure 1, the invention is shown as 55 applied to a lamp having a reflector 2, of the ordinary parabolic kind, and a source

of light 3, a similar parabolic reflector and light is used in each of the other figures. The parallel rays intercepting conical reflector is shown at 4, and as shown in Figure 1, this conical reflector which also forms the obturator is held in place in the centre of the lamp glass 5 by means of a bolt and nut 6, the bolt passing through the axis of the conical reflector 4, and through a centring block 7, of wood or other suitable material and also through a hole in the centre of the glass 5.

A washer 8, is arranged on the outside of the glass 5, and between this washer and the glass and also between the centring block 7, and the glass 5, packing discs of soft material such as felt or cloth are provided. The annular conical reflector is shown at 9, and is designed at its smaller diameter to fit in the open end of the parabolic reflector 2, in any suitable manner, for instance, in the manner in which the glass or lens is usually fitted. The larger diameter of the annular reflector 9 is formed with a recess 80 to receive the edge of the glass disc 5, and the glass disc is held in this recess by means of a flanged ring 10, secured by a bayonet joint or in any suitable manner on the periphery of the glass receiving recess in the 85 annular reflector 9.

In this example, the illuminating or projected beam rays are projected from an annular conical reflector 9, of which the angle of the cone is 90°, and its smaller diameter 90 is equal to that of the open end of the parabolic reflector 2, while its larger diameter is double the size of the smaller one, so that the cross sectional area of the beam at the lamp glass will be about three times that 95 of the open end of the parabolic reflector, and being divided over a greater area a considerable reduction in glare will be effected for this reason as well as for the fact that all the direct rays from the parabolic reflector do not reach the eye being intercepted by the conical reflector 4, acting as an obturator. The larger or the annular reflector 9, may, however, be of any other size 100 that will give an annular base or cross section of projected beam of larger than the light opening or base of the ordinary parabolic reflector 2.

The annular reflector 9, can be so designed as to give an annular beam of which the central dark portion formed by the intercepting reflector 4, will be in the form of a 110

cone thereby gradually decreasing in diameter until at a given distance it will disappear and the projected light will continue therefrom as one of circular cross section 5 at the desired range. The annular reflector can be designed to give a beam of which the outer portion is of any desired divergency.

In order to bring the projected beam rays to cover the same illuminated area at the 10 desired range as would be covered by the parabolic reflector the angles and shape of the conical and annular reflectors are correspondingly designed. In the present example to effect this object, the conical sides 15 of the surface of the annular reflector being straight, those of the inner cone are slightly curved correspondingly, the difference between the angles of the conical and annular reflectors at points where they receive and 20 reflect any particular ray, in accordance with a well known principle, is equal to twice the angle of the beam ray to the horizontal.

In Figure 1, the beam rays in any particular plane passing through the axes of 25 the reflectors are projected from a radial line which for a vertical plane is the line 13, 14, formed by the intersection of the plane with the annular reflector 9, so that any diametral line such as 15, 16, on the 30 illuminated area at the desired range will be illuminated from two oppositely disposed radial lines as 13, 14, and 17, 18, on the annular reflector 9, this will render the distribution of the light more uniform, and 35 compensate to a considerable extent for inaccuracies in the reflecting surfaces and in their co-axial alignment.

The rays projected from the annular reflector 9, from any particular radius there- 40 on may, however, be distributed over a corresponding radius of the area of the illumination as illustrated by Figure 2.

In some types of large lamps it may be desirable to reduce the depth of the conical 45 and annular reflectors, and this may be effected as illustrated by Figure 3, wherein they are reduced to one half the depth of those shown in Figures 1, and 2, and in the intervening space is concentrically supported an annular reflector 94, having inner 50 and outer conical reflecting surfaces designed to give by their combined effect the same illuminated area at the desired range as given by only one pair of inner and outer reflectors.

Only one intermediate annular reflector 94, is shown, but more may be used, each constituting on its outer side an inner conical reflector for the next larger annular reflector, and on its inner side an annular reflector for the next smaller conical reflector, all the reflectors in the series being designed to produce annular beams of light which combine to form one single beam.

65 These intermediate annular conical re-

flectors may be supported concentrically in the same plane by means of thin radial wires, or they may be supported by fastening devices passing through holes in glass of the lamp.

The bases of the conical and annular reflectors may be arranged in or near the same plane.

In the example shown in Figures 1 to 3, some of the rays radiating directly from the 75 source of light will pass out at an angle through the glass and may be used for local illumination near the lamp. Such direct rays may, however, be entirely cut out by designing the lamp as illustrated in Figure 80 4, wherein the position of the parabolic reflector 2, is reversed, and the base of the annular conical reflector 9, oppositely disposed to that of the inner conical reflector 4.

In Figure 5, is shown a modification of the 85 lamp shown in Figure 4, the conical reflectors 9, and 4, being substituted by an annular parabolic reflector 9, 4. The central portion of the annular reflector 9, 4, that is the portion within a co-axial cylindrical 90 surface passing through the foci of the parabolic lines generating the annular reflector, forms the inner cone 4, while the portion thereof without the cylindrical surface forms the annular conical reflector 9. 95

It will be understood from the above that the conical intercepting reflector 4, can be made of straight or curved sides and the annular reflector 9, can also be made of straight or curved sides according to the character of 100 the beam desired, and the two can be combined and made of one piece of transparent material such as an optical glass plate or disc having its inner and outer edges of the same shape as the conical reflectors, and prepared 105 as surfaces adapted to reflect light through the glass plate or disc.

The glass front of the casing as illustrated is a plane disc, it may, however, be an annular piece of plate glass arranged to cover 110 the space between the bases of the inner and outer conical reflectors, and in order to facilitate cleaning is preferably made detachable in any suitable manner such as used at present for lamp fronts or lenses. The inner 115 or intercepting reflector is preferably constructed with a base of less diameter than the inside of the open end of the parabolic reflector, and may be secured in position at the centre of the glass front of the casing, 120 either directly thereto as shown in Figure 1, or by other suitable means.

What I claim is:—

1. A light projector comprising a parabolic reflector, a frusto conical reflector at 125 and around the open end of the parabolic reflector and attached thereto and a conical reflector arranged coaxially of the parabolic and frusto conical reflectors and in the latter and also forming an obturator, the sur- 130

face of said conical reflector and obturator being parallel with the inner surface of the frusto-conical reflector and the apex of said conical reflector and obturator being presented toward the smaller end of the parabolic reflector.

2. A light projector comprising a parabolic reflector, a source of light therein near its smaller end, to project a beam therefrom, 10 a conical reflector arranged coaxially with and at the open end of the parabolic reflector, and a frusto conical reflector arranged around said parabolic and conical reflectors and at the open end of the former, 15 the said conical reflector also forming an obturator, the surface of said conical reflector and obturator being parallel with the inner surface of the frusto-conical reflector and the apex of said conical reflector, and 20 obturator being presented toward the smaller end of the parabolic reflector.

3. A beam projecting lamp comprising in

combination a parabolic reflector adapted to contain the light source of the projected beam, a light obturator, two concentric convex conical reflectors, and two concentric annular concave conical reflectors, the five reflectors and the obturator being co-axially arranged and the convex and concave conical reflectors arranged concentrically within 25 the annular reflector at the open end of the parabolic reflector, and so constructed and associated with respect to one another that both convex conical reflectors will act as the obturator to divide portions of the rays projected directly from the source of light by the parabolic reflector, but each will reflect its portion of such rays radially outwards onto its adjacent annular concave reflector which will reflect the two portions of the 30 rays to combine to form the projected beam over the edge of the obturator.

In witness whereof I affix my signature.

JOHN GEORGE SMITH.
